Primary Examiner — Marissa J Cash(74) *Attorney, Agent, or Firm* — Novick, Kim & Lee, PLLC; Allen Xue; Hyun Woo Shin(57) **CLAIM**

We claim the ornamental design for an electronic cigarette, as shown and described.

DESCRIPTION

FIG. 1 is a top perspective view of an electronic cigarette, showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings show portions of the electronic cigarette which form no part of the claimed design.

1 Claim, 8 Drawing Sheets(56)
